CLAIM

The ornamental design for a coin wrapping machine, as shown and described.

DESCRIPTION

FIG. 1 is a perspective view of a coin wrapping machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged portion view of encircled portion labeled, "9," in FIG. 1.

The dash-dash broken lines in the drawings depict portions of the coin wrapping machine that form no part of the claimed design.

The dot-dash broken lines represent boundaries of the enlarged portion view of FIG. 9 shown in FIGS. 1 and 9 and form no part of the claimed design.
